CLAIM

What is claimed is the ornamental design for a lumbar traction device, as shown and described.

DESCRIPTION

FIG. 1 is a front perspective view of a lumbar traction device in a start position showing a new design;
FIG. 2 is a rear perspective view in the start position thereof;
FIG. 3 is a top view in the start position thereof;
FIG. 4 is a bottom view in the start position thereof;
FIG. 5 is a right side view in the start position thereof;
FIG. 6 is a left side view in the start position thereof;
FIG. 7 is a front side view in the start position thereof;
FIG. 8 is a rear side view in the start position thereof;
FIG. 9 is a front perspective view in an end position thereof;
FIG. 10 is a rear perspective view in the end position thereof;
FIG. 11 is a top view in the end position thereof;
FIG. 12 is a right side view in the end position thereof; and,
FIG. 13 is a left side view in the end position thereof.
In the drawings, the broken lines depict environmental subject matter only and form no part of the claimed design.
